UNITED STATES PATENT OFFICE.

TOM WILSON, OF PHILADELPHIA, PENNSYLVANIA, ASSIGNOR TO BETHLEHEM STEEL COMPANY, A CORPORATION OF PENNSYLVANIA.

FURNACE PORT AND METHOD OF OPERATING THE SAME.

Application filed February 2, 1922. Serial No. 533,517.

My invention relates to the construction of heating, melting or other furnaces with special reference to the port construction thereof, but for the sake of simplicity of description and illustration, I will herein refer to its use in connection with an open hearth steel melting furnace, but wish it understood that it is equally applicable to other types of furnaces and the port constructions thereof. One of the objects of my invention is to so design and arrange the ports and ends of the furnace that they will not be destroyed by the heat of the outgoing gases, and one of the means which I provide to this effect is to make the constructions such that the exit ports are of much larger size and area than those which supply the combustibles to the other end, and the ports are also adjustable in size.

In accordance with my construction the inlet ports which supply air and combustible gases to the furnace are of smaller area than the exit ports, and the air and gas are traversed through the entering ports at a comparatively high velocity and in such a way as to provide a thorough mixture thereof and consequently prompt combustion with the resultant high temperature, and by means of my construction the inlet of gases can be so arranged as to produce a shorter flame so that the hot part or apex of the flame does not impinge against the outgoing end of the furnace, which thereby prevents the destruction of the same. As a result of this construction the gases are burned in an economical manner and a considerable economy of fuel is obtained. Another advantage of my construction is that the outgoing ports, which may be of large area, as before stated, do not throttle the flow of gases through the furnace, and also allow the gases to be thoroughly burned and expanded within the furnace and permit the products of combustion to escape quickly therefrom.

My construction is also such that the outgoing products of combustion do not impinge against the entering gas ports, for the reason that these parts of the construction are so arranged that they are lifted upwardly and out of the line of travel of the outgoing gases at the exit end.

My furnace is of the regenerative or recuperative type and subject to the usual reversing flow of gases therein; for example,

the combustible gases are delivered at one end of the furnace and mixed there and form a flame which passes into the furnace, and at this time the products of combustion pass out at the other end, and after a suitable interval of time the flow of gases is reversed as is customary. The air and combustible gases, as above stated, are preferably heated by regenerators or recuperators in the usual way and the reversal may be accomplished by any of the well-known means for this purpose.

As a result of my construction the action of the furnace is very rapid, either for melting or heating, and I can use in it producer gas, which ordinarily is regenerated, or if desired I may use natural gas, coke oven gas, oil gas or other gases of high calorific power, which do not need to be regenerated or preheated.

The adjustable ports of my furnace are preferably made of metal and water cooled, and seated upon or against fixed portions of the construction, which may also be water-cooled.

Having thus given a general description of my invention, I will now, in order to make the matter more clear, refer to the annexed sheet of drawings, which forms part of this specification, and in which like characters refer to like parts:

Figure 1 is a vertical longitudinal sectional elevation of an open hearth furnace with the central portion broken away, illustrating the application of my invention, taken on the line I—I of Figure 2; Figure 2 is a horizontal sectional plan taken on the line II—II of Figure 1; Figure 3 is a transverse sectional elevation taken on the line III—III of Figure 1; Figure 4 is a transverse sectional elevation similar to that of Figure 3, showing a modified form of construction with only one gas burner at each end; Figure 5 is a vertical longitudinal sectional elevation of a slightly modified form of furnace construction taken on the line V—V of Figure 6, showing one burner at each end of the furnace and with the regulating slide made in two sections instead of in one piece as in the prior figures; Figure 6 is a horizontal sectional plan taken on the line VI—VI of Figure 5; Figure 7 is a transverse sectional plan taken on the line VII—VII of Figure 6, and Figure 8 is

a transverse sectional elevation similar to Figure 7, but showing two burners and the slides arranged in three parts.

The gas burners in Figs. 1, 2, 3 and 4 have 5 round noses or exits, while those of Figures 5, 6, 7 and 8 have rectangular exits, and all are of elbow shape.

Referring now to the characters of reference on the drawings:—1 indicates the furnace as a whole, 2 is the hearth and 3 the roof thereof. The throats or mixing chambers at each end of the furnace are 4, into which the mixed gases first issue at the entering end and through which the products of 15 combustion pass at the other end.

As illustrated in Figures 1, 2, 3 and 4, I provide a ported slide 5 having ports or openings 6 therein, which is preferably made of metal construction and operates in 20 a groove or slideway 7, which guides it in its up and down movement, these slides being water-cooled and provided with pipe connections 8 for supplying water thereto and exhausting the same therefrom, which 25 water may be furnished from any convenient source. The pipes 8 may also be connected to means for raising and lowering them to thereby regulate the position of the slides either in their up or down position, 30 or in intermediate positions as desired. At each end of the furnace, as shown in Figures 1, 2 and 3, I provide two burners 9, which are also of metal plate, provided with beveled lower surfaces 10, adapted to be seated 35 on the seats 11 of the water-cooled seat rings 12, which are mounted on the brick-work at the ends of the gas channels, as shown. 13 are the water-cooling circulating pipes connected to the hollow seat rings 40 12, and 14 are the water pipes connected to the burners 9, which pipes 14 may also be used to raise and lower the burners as may be desired. At each end of the furnace I provide a somewhat roomy air chamber 15, 45 built in the brickwork thereof and communicating therewith are the air channels 16, which may be connected to the usual air recuperator or regenerator, reversing valves and other customary flues and constructions. 50 I also provide a gas inlet channel 17, which may be connected to the gas regenerator or recuperator, gas reversing valve and other customary flues. In front of the slides 5 I preferably arrange a water-cooled box 18, 55 provided with water-circulating pipes 19, and these serve to further protect the slides and other adjacent portions of the furnace.

The slide illustrated in Figures 1, 2, 3 and 4 is made in one piece, having openings or 60 ports 6 therein adjacent to the gas burners 9, so that when the slide is raised all portions thereof move simultaneously in order to regulate the flow of gases.

As illustrated in Figures 5, 6 and 7, the 65 slides at each end of the furnace are made in

two sections 20 with spaces 21 therebetween to accommodate the burner 9, and these therefore may be regulated separately if desired in order to more correctly control the flow of gases, and these slides 20 are provided with water-pipe connections 22 for the purpose of cooling, raising and lowering them in any manner similar to that previously described. In this case, however, the water-cooled seat ring 24 is provided 70 with a flat side and a burner 9 is provided with a corresponding flat bottom 23 to be seated thereon.

As illustrated in Figures 6, 7 and 8; 25 80 are air inlet channels which connect the air regenerators or the recuperators with air chambers 15.

As illustrated in Figure 8, the slides 20 are made in three sections in order to accommodate two burners 9 at each end of the 85 furnace, and these may also be regulated separately for the purpose of controlling the gas flow as desired.

The water supply to the cooling and lifting pipes may be furnished from any source, 90 and the pipes which lift and lower the slides and burners may be operated by any suitable mechanism, while the customary slag pockets, reversing valves, regulating valves, connecting flues, etc., may be used, 95 although the details thereof are not illustrated or described herein.

It should also be noted, as illustrated in Figure 2, that I show one wide air channel at each end of the furnace, whereas in Figure 6 I show two of these, 25, at each end, and while the gas ports and seats of Figures 1, 2, 3 and 4 are round in their outline, those of Figures 5, 6, 7 and 8 are rectangular.

Other advantages of my construction are 105 that the gas burners are movable and none of the waste gases or products of combustion from the furnace have to pass through the restricted openings of the gas burners, and when the gas burners and slides are 110 lifted into their high position large outlet areas are provided for the passage of the outgoing gases. When the slides are down or partly down they are so arranged as to restrict the openings for the incoming air and 115 to concentrate this air over and around the burners, thus providing a better mixture and better combustion. When the slides and burners are in their high position the area for the outgoing gases is substantially the 120 entire width of the furnace, which, therefore, in addition to providing a large outlet as previously mentioned, also serves to distribute the flame over the hearth.

The operation of the furnace construction in accordance with my invention is as 125 follows:—Referring to Figures 1 and 5, the burner 9 at the right hand end of the furnace is seated on the water-cooled seat ring in its lower position and the slide 5 or 20 130

at that end is also in its lower position, while the corresponding parts at the other end of the furnace are raised and in a position such that the outgoing products of combustion 5 cannot contact with them, and they are thereby free from the possibility of damage on this account. At this time heated combustible gases pass upwardly through the right hand channel 17 into the burner 9, and 10 by reason of the elbow shape of the burner the gases are deflected to the left and enter into the mixing chamber 4. At this time air is also passing upwardly through the right hand flue 16 into the chamber 15 and 15 thence passes over the burner 9 and around its sides and mixes with the heated gases issuing from the burner, and the mixture then issues into the furnace with high velocity and rapid combustion at once ensues. If more air is desired the slide 5 or 20 can be raised a little. The products of combustion then pass downwardly through the left hand channels 16 and 17 to the air and gas regenerators or recuperators 25 respectively and heat them prior to the reversal of the flow.

As illustrated in Figures 5, 6, and 7, the slides 20 may be operated independently, and if more air is needed at one side of the 30 furnace than at the other, the slide at that side can be opened to admit more air, and this is similarly true of the construction shown in Figure 8, in which any of the slides 20 can be arranged in any position 35 desired to admit the amount of air deemed necessary. The control of the amount of gas is regulated, of course, by the gas valve outside of the furnace as is customary. After the operation has proceeded in this 40 manner for the required length of time, the flow in the furnace may be reversed by raising the burner 9 and the slides 5 or 20 at the right hand side and lowering the burner 9 on its seat at the left hand side and lowering 45 the left hand slides 5 or 20 to any extent as desired, and moving the reversing valves to their other positions, whereupon the operation proceeds in the reverse direction.

The construction of my furnace is such 50 that a so-called blow pipe flame is provided whereby a thorough mixture of air and gas is provided and the hottest part of the flame may be arranged to terminate within the hearth of the furnace so that the products 55 of combustion will not destroy the outlet portions. The air also substantially surrounds the gas, thus causing a thorough mixture, while also protecting the ports, roof and other parts as the air is cooler than the 60 regenerated gases.

Although I have described and illustrated 65 my invention in considerable detail, I do not wish to be limited to the exact and specific details thereof, as shown and described, but

for, or equivalents thereof, as are embraced within the scope of my invention or as pointed out in the claims.

Having thus described my invention, what I claim and desire to secure by Letters Patent is:—

1. In a reversible regenerative furnace, in combination, a combustion chamber having an opening at each end through which fuel may be introduced or through which 75 products of combustion may escape, a fuel port at each end of the furnace, each such port being movable so that it may be positioned to direct a stream of fuel toward the combustion chamber or may be withdrawn 80 out of the direct path of the products of combustion, an air supply channel at each end of the furnace leading toward said opening, and a damper at each end of the furnace and movable relatively to the fuel 85 port and furnace body so that it may be positioned to direct the stream of inflowing air toward the stream of inflowing fuel or may be removed from the path of the stream of products of combustion, the said damper 90 having an aperture formed therein so positioned that the stream of incoming fuel flows directly therethrough when the damper is in its air directing position.

2. The combination set forth in claim 1 in 95 which the damper is substantially flat and is disposed in advance of the mouth of the gas port.

3. In a reversible regenerative furnace, in combination, a combustion chamber having 100 an opening at each end through which fuel may be introduced or through which products of combustion may escape, a fuel port at each end of the furnace adapted to discharge fuel adjacent that opening which for 105 the time being is serving as an inlet, an air supply channel at each end of the furnace leading toward said opening, and a damper at each end of the furnace and movable relatively to the furnace body so that it 110 may be positioned to direct the stream of inflowing air toward the stream of inflowing fuel or may be removed from the path of the stream of products of combustion, the said damper having an aperture 115 therein comprising a notch in the lower edge thereof so positioned that it lies directly in advance of the inflowing fuel stream, said aperture constituting a restricted port for fuel and air and promoting complete admixture thereof.

4. In a reversible regenerative furnace, in combination, a combustion chamber having an opening at each end through which fuel 125 may be introduced or through which products of combustion may escape, a fuel port at each end of the furnace, each such port being movable so that it may be positioned to direct a stream of fuel toward the combustion chamber or may be withdrawn out 130

of the direct path of the products of combustion, an air supply channel at each end of the furnace leading toward said opening, and a damper at each end of the furnace 5 and movable relatively to the fuel port and furnace body so that it may be positioned to direct the stream of inflowing air toward the stream of inflowing fuel or may be removed from the path of the stream of products of combustion.

5. In a reversible regenerative furnace, in combination, a combustion chamber, regenerators, channels connecting the ends of the combustion chamber respectively, to the 15 regenerators, each such channel serving alternately as a conduit for conducting heated air to the combustion chamber or products of combustion to the connected regenerator, a fuel port positioned in that 20 channel which is for the time being conducting air to the combustion chamber and positioned to discharge fuel toward the combustion chamber, and means for directing the heated air into the stream of fuel, 25 comprising a damper positioned in said channel and extending from one side wall to the other, said damper having a single aperture centrally arranged directly in front of the fuel port and extending to the 30 lower edge of the damper through which the fuel is constrained to pass on its way to the combustion chamber, and being removable from the path of products of combustion when the furnace is reversed.

35. 6. In a reversible regenerative furnace, in combination, a combustion chamber, regenerators, channels connecting the ends of the combustion chamber respectively, to the regenerators and serving alternately as conduits for conducting heated air to the combustion chamber or products of combustion to the connected regenerator, means for introducing a stream of gaseous fuel under pressure into that channel which for the time 45 being is serving to conduct heated air to the combustion chamber, the gaseous stream moving directly toward the combustion chamber, and means for bringing about a quick and intimate mixture of the gas and 50 heated air, said means comprising a damper provided with an aperture formed as a notch in the lower end thereof and so located that

the stream of gaseous fuel passes directly therethrough without being intercepted thereby and through which the air for combustion is likewise constrained to pass on its ways to the combustion chamber, said aperture being of materially less area than the normal cross sectional area of the channel, and the damper being adapted to be 60 moved when the furnace is reversed to restore the channel to its normal effective cross sectional area.

7. An end construction for a reversible regenerative furnace comprising an air port 65 in communication with the combustion chamber, the roof of the air port being offset upwardly relatively to the roof of the combustion chamber, a substantially vertical wall connecting the roof of the combustion 70 chamber and the roof of the air port, and a damper movable in a substantially vertical plane to a position parallel and adjacent to said wall or to a position to partially block communication between the air port and 75 combustion chamber, the damper when in the first mentioned position lying wholly out of the path of products of combustion.

8. The combination set forth in claim 7 in which the vertical wall comprises a water 80 cooled metallic shell.

9. An end construction for open hearth regenerative furnaces comprising an air port, a furnace port communicating therewith, the floor of said ports being substantially in the same horizontal plane but the roof of the air port being substantially raised above the roof of the furnace port, a gas uptake opening through the floor of the furnace port, a water cooled gas port 90 adapted to register with the mouth of the gas uptake, and means for lifting said gas port toward the roof of the air port to a position above the top of the furnace port, in which position it lies out of the direct 95 path of products of combustion.

10. The combination set forth in claim 9 in which a water cooled seat for said gas port encircles the mouth of the gas uptake and rests on the floor of the air port. 100
In witness whereof I hereunto affix my

signature.

TOM WILSON.
